United States Patent Office

Des. 186,432
Patented Oct. 27, 1959

186,432

BUILDING BLOCK

William Mileto, Vernon Center, Conn., assignor to Plasti-
crete Corporation, Hamden, Conn., a corporation of
Connecticut

Application April 8, 1959, Serial No. 55,414

Term of patent 14 years

(Cl. D18—2)

Fig. 1.

Fig. 2.

Fig. 1 is a perspective view of a building block embodying my new design; and

Fig. 2 is a front elevational view of the block.

I claim:

The ornamental design for a building block, substan-
tially as shown.
